CLAIM

The ornamental design for a hot tub spa as shown and described.

DESCRIPTION

The patent or application file contains at least one drawing executed in color. Copies of this patent or patent application publication with color drawing(s) will be provided by the Office upon request and payment of the necessary fee.

1. Hot tub spa

1.1 : Front-right perspective view

1.2 : Front perspective view

1.3 : Rear-right perspective view

1.4 : Front

1.5 : Back

1.6 : Left

1.7 : Right

1.8 : Top

1.9 : Front-right perspective view

1.10 : Front perspective view

1.11 : Rear-right perspective view

1.12 : Front

1.13 : Back

1.14 : Left

1.15 : Right

Reproductions 1.1 to 1.15 show a hot tub spa with an integrated cover that is movable vertically between a lower (closed) position and an upper (open/deployed) position; reproductions 1.1 to 1.8 show the hot tub spa with the cover in the closed position, while reproductions 1.9 to 1.15 show the hot tub spa with the cover in the open/deployed position. The green color depicts portions of the hot tub spa that form no part of the claimed design.
